UNITED STATES PATENT OFFICE.

EUGENE A. CROWE, OF BROOKLYN, NEW YORK, ASSIGNOR TO THE E. S.
HIGGINS CARPET COMPANY, OF NEW YORK, N. Y.

DESIGN FOR CARPET.

SPECIFICATION forming part of Design No. 28,278, dated February 8, 1898.

Application filed December 27, 1897. Serial No. 663,769. Term of patent 3½ years.

To all whom it may concern:

Be it known that I, EUGENE A. CROWE, a citizen of the United States, residing at Brooklyn, in the county of Kings and State of New York, have invented and produced a new and original Design for Carpets, of which the following is a specification, reference being had to the accompanying drawing, forming a part thereof, which represents a face view of a carpet in which my new design is embodied.

The invention relates to a design to be worked into or upon surfaces such as carpets and similar fabrics; and it consists of the novel conformation of the figures, as herein shown and claimed.

The main figure is a rosette figure A, comprising a floral center and foliate fringe. Op-

posing triangular fanciful groups of leaves B and B' are arranged at one side of the rosette figure, and minor groupings C and C', also of fanciful leaves, are arranged at the other side of the rosette figure. Between the rosette figure A and the groups of fanciful leaves B and B' and C and C' irregular checkering a appears, associated with scrolls a', the checkering and scrolls apparently constituting a framing for the rosette figure.

I claim—

The design for carpet substantially as shown.

EUGENE A. CROWE.
